UNITED STATES PATENT OFFICE.

WILLIAM A. BORDEN AND CLAUDIUS H. M. ROBERTS, OF THE UNITED STATES ARMY.

BOMB BODY.

Application filed June 27, 1922. Serial No. 571,223.

(FILED UNDER THE ACT OF MARCH 3, 1883, 22 STAT. L., 625.)

To all whom it may concern:

Be it known that we, WILLIAM A. BORDEN, major, Ordnance Department, United States Army, and CLAUDIUS H. M. ROBERTS, captain, Ordnance Department, United States Army, citizens of the United States, stationed at Washington, District of Columbia, have invented an Improvement in a Bomb Body, of which the following is a specification.

10 The invention described herein may be used by the Government, or any of its officers or employees in prosecution of work for the Government, or by any other person in the United States, without payment to us of any royalty thereon, in accordance with the act of March 3, 1883.

The subject of this invention is a bomb and the invention relates more specifically to the construction of a bomb body.

20 In the construction of a bomb body it is necessary that the body be so designed that it will assume a proper position during flight; that it possesses rigidity; that it is susceptible of quantity production and that 25 the parts of the body may be easily and readily assembled.

The present invention has been devised to accomplish these desired results, specifically, by providing a body of drawn tubing to 30 which the nose and base may be easily attached or which may be spun or swaged to form a nose.

With these and other objects in view, which will hereinafter more fully appear, the invention resides in the novel arrangement and combination of parts and in the details of construction hereinafter described and claimed, it being understood that changes in the precise embodiment of the invention 40 herein disclosed may be made within the scope of what is claimed without departing from the spirit of the invention.

Practical embodiments of our invention are illustrated in the accompanying drawings, wherein:

Fig. 1 is a view in side elevation of a bomb constructed in accordance with our invention;

Fig. 2 is an enlarged detailed view in longitudinal section of the nose and a fragment of the body;

Fig. 3 is a section on the line 3—3 of Fig. 2;

Fig. 4 is a fragmentary view in side elevation, partly in section, of the base and fin assembly of the bomb;

Figs. 5, 6 and 7 are sections on the lines 5—5; 6—6; and 7—7, respectively of Fig. 4;

Fig. 8 is a longitudinal section of a modified form of bomb body;

Fig. 9 is a fragmentary detail sectional view of the base and adapter;

Fig. 10 is a similar view of the structure for locking the base cap in place;

Fig. 11 is a sectional view of the carrying lug, showing a fragment of the body to which it is attached;

Fig. 12 is a view in elevation of the lug.

In carrying out our invention we prefer to provide a body 10 of drawn tubing, conveniently steel, to the forward end of which is attached the nose piece 11. A desirable form of attachment, as herein shown, is provided by reducing the end of the nose piece, as indicated at 12, Fig. 2, so that the same 75 may telescope within the forward end of the body 10 and the parts then connected together by welding as at 13, and further secured by rivets 14 passed through the telescoping portions which are drilled or otherwise apertured for that purpose.

The forward end of the nose piece is adapted to receive an adapter 15 to which a booster 16 may be connected and the forward end of which has connection with a bearing member 17 in which the fuse mechanism is journaled and which may be supplied with eyes 18 for the reception of the end of a safety wire 18'.

The rear end of the body 10 is closed by a base plug 19 which telescopes into the rear end of the body and which may be welded thereto as indicated at 20.

The base plug is preferably formed with a slightly tapered, rearwardly extending, annular flange 21 to provide a seat for a purpose hereinafter set forth, and it is also centrally apertured and tapped to receive an adapter 22 to the inner end of which may be connected a booster 23 and to the outer 100 end of which is connected a tubular rod 24.

The tubular rod acts as a housing for the base fuse mechanism and has its outer end threaded to receive a nut 25 which engages the rear end of a base cap 26 the 105 forward end of which cap embraces the

tapered flange 21, to hold the cap firmly in place. The base cap has connected thereto the stabilizers or fins 27.

The base cap 26 is preferably made up 5 of a single sheet rolled to form a cone and the meeting edges butt welded. Angle pieces 28 are connected by welding or riveting or both to the cap and between them the inner edges of the stabilizers or fins are 10 secured. When, as illustrated herein, the fins extend for a considerable distance to the rear of the base cap, such extending portions may be bound together by angle pieces 29 which are placed in the angles formed 15 at adjoining edges of adjacent fins and are securely bound together upon the fins by riveting. The fins may be further secured against flexure or distortion by braces 30 which extend diagonally between adjacent 20 fins to which they are connected in any suitable manner as by riveting.

For the purpose of hanging bombs from the carrier or rack of an aircraft, a lug or lugs 31 may be provided. These lugs 25 are to be attached to the body in the field and to provide a ready attachment of these lugs the body is tapped as at 32 for the reception of studs 33, having heads 34 formed with reduced necks 34'. In order 30 that undue strain may not be placed upon the parts when the lugs are attached, due to the use of too large a wrench or the like, the necks 34' are sufficiently reduced in thickness to cause them to shear when a 35 strain in excess of that calculated is applied. The tapped apertures 32 may be conveniently closed at their inner ends by a plate 35 which is welded or otherwise secured to the interior face of the body thus protecting the explosive contained in the body 40 from exposure.

The base fuse casing 36 may be properly located and held within the tube 24 by means of a tubular plug 37 which is forced 45 into the rear end of the body and encircles the casing.

In the modified form shown in Fig. 8, the body 10 is drawn to a tube and the forward end is spun or swaged to form the 50 nose 11 which is apertured at 38 and tapped

for the reception of an adapter or closure plug. The base and fin assembly are assembled to this form of body as heretofore described in relation to the preferred form.

We claim:

1. A bomb, including a body portion provided with a tapered nose, apertured to receive an adapter, a base plug secured in the rear end of the body, said plug formed with a rearwardly extending tapered annular 60 flange, a tubular rod connected to the base plug, a base cap seated on the flange, fins secured to the base cap and means engaging the rod for securing the base cap in place.

2. A bomb, including a drawn tubular body portion provided at its forward end with a tapered nose, a base plug secured in the rear end of the body portion, said base plug formed with an annular seat, a base 70 cap engaging said seat, fins secured to the base cap and detachable means connected to the plug and engaging the cap for securing the cap in place.

3. A bomb, including a drawn tubular body portion, provided at its forward end with a tapered nose, a base plug secured in the rear end of the body portion, said base plug formed with an annular seat, a base cap 75 engaging said seat, fins secured to the base cap and means connected to the plug and engaging the cap for securing the cap in place.

4. A bomb, including a drawn tubular body portion, provided at its forward end 80 with a tapered nose, a base plug secured in the rear end of the body portion and a base cap and fin assembly detachably secured to the base plug.

5. A bomb, including a drawn tubular 85 body portion, a tapered nose having its rear end telescoping into the forward end of the body portion, means engaging the telescoping portion of the body and nose for securing the parts together, a base plug secured in the rear end of the tubular body portion and a base cap and fin assembly 90 secured to the plug.

WILLIAM A. BORDEN.

CLAUDIUS H. M. ROBERTS.
